UNITED STATES PATENT OFFICE

2,682,210

BOXMAKING MACHINE

Elbert L. Bivans, Los Angeles, Calif., assignor to
 E. L. Bivans, Inc., a corporation of California

Application February 5, 1951, Serial No. 209,343

13 Claims. (Cl. 93—49)

1

The invention relates to a box-making machine and more particularly to a machine for operating on paste-board boxes which are folded flat, the operation consisting in erecting or opening the box and also in tucking in the side flaps and the end flap at one end of the box. The invention is an improvement on the box machine disclosed and claimed in co-pending application S. N. 140,073 filed January 23, 1950.

In the box machine of said patent application, in certain special cases, the end tucker cannot tuck in the end flap. One of these cases exists where the folded boxes are deformed so that when the four sides thereof are erected, the uppermost front of the box is concave. In this case, the end flap would not move in low enough to tuck under the concave front of the box. In another case, certain special boxes have a comparatively long end flap and a small distance from the front to the back of the box. The former machine would not tuck the end flap in a box of this type. One object of the present invention is to overcome these difficulties and provide an end tucker which will tuck in the end flaps under the circumstances above stated and for different types of shallow or deep boxes. This is accomplished by providing a primary end tucker and a secondary end tucker to effect the tucking in two steps. The end flap has two fold lines, one where the flap joins the box and the other near the end of the flap. The primary tucker folds the flap at its outer fold line and moves to form a guide leading into the box. The secondary tucker completes the tucking operation while the end of the flap is being guided into the box by the primary tucker. To handle a box having a concave or low front, the guide comes to a position underneath such front and the secondary guide in completing the tucking operation, raises the guide so that the box front is at its normal position to receive the end of the flap.

The invention provides a number of other improvements as will appear from the drawings and the following description.

For further details of the invention reference may be made to the drawings wherein Fig. 1 is a plan view of a box-making machine according to the present invention, with parts broken away.

Fig. 2 is a sectional view on line 2—2 of Fig. 1.

Fig. 3 is a sectional view on line 3—3 of Fig. 2.

Fig. 4 is a vertical sectional view across the feed device and bed of the machine, with parts broken away.

Fig. 5 is a sectional view on line 5—5 of Fig. 3.

Figs. 6, 7 and 9 are sections on lines of the corresponding numbers in Fig. 5.

2

Fig. 8 is a perspective view showing the box and flap folding devices.

Fig. 10 is a sectional view corresponding to Fig. 9, with the end flap tuckers in another position.

Fig. 11 is a view like Fig. 10 showing the end tuckers in final tucking position.

Fig. 12 is an enlarged sectional view on line 12—12 of Fig. 1.

The same form of end flap tucker is shown in Figs. 9 to 12.

Figs. 13, 14 and 15 are vertical sectional views like Fig. 12 of a modification for tucking the end flap under the front of a shallow box or under the concave front of a box.

Fig. 16 is a perspective view of a box having a concave front and for which the tuckers of Figs. 13, 14 and 15 have been provided.

Fig. 17 is an exploded perspective view of the end tucker of Figs. 13 to 15.

Figs. 18 and 19 are sectional views of a further modification for operating on a shallow box, these figures showing the end tuckers in different positions.

Referring in detail to the drawings, the box-making machine comprises a rectangular casing 1 mounted on rollers 2. The casing 1 has a top 3 having a magazine 4 for a stack 17 of collapsed boxes like 5, also a folding station 6 where the collapsed box is expanded to open position and the side flaps 7 and 8, see Fig. 1 and the bottom end flap 9 are tucked in. The box thus opened and tucked ready for ejection is shown in Fig. 11 although the end tuckers would first be moved away from the end of the box.

The box blanks 5 are fed one at a time from the bottom of the stack 17 by means of a fork 18 which rides in an opening 20 in the bed 21 adjusted to fit a given box. The fork 18 is carried by a runner bar 22, see Fig. 2, driven through a suitable crank and lever system 23 by a motor 24. The speed of motor 24 can be changed by a controller 25. The drive for the fork 18 is disclosed and claimed in the above mentioned co-pending application and forms no part of the present invention.

The motor 24 through suitable belts or pulleys as indicated in Fig. 2 drives a pulley 26, see Fig. 2 also Fig. 5, on a countershaft 27 which carries all of the various cams for operating the tucking devices. The shaft 27 is mounted in suitable bearings like 28, 29 carried by the framework 30 of the casing 1. Cam 31, see Figs. 3 and 5, operates the side tuckers 32, 33 in and out, these tuckers being operated by a bell crank 34 having a link 35 connected to a lever 38 having a cam follower 36. The cam follower 36 is urged on

the cam 31 by a spring 37. The spring 37 urges the tuckers 32 and 33 out, driving dwell 39 but is not sufficient to retract these tuckers if boxes are jammed at the folding station 6. To overcome this, as shown in Figs. 5 and 7, the cam 31 is provided with an overhang 40 to provide a groove 41 in which the cam follower 36 rides, to positively operate the side tuckers 32 and 33 and permit the ejection of a faulty box so that subsequent operations will be normal without stopping the machine.

As shown in Fig. 3, the side tucker 32 is carried by a slide 42 connected through a link 43 with one side of bell crank 34. The other side tucker 33 not only moves in and out but also up and down, as described and claimed in the above patent application. The side flap tucker 33 is shown in Figs. 3, 6 and 8, is carried by an oscillating arm 50 having a hinge connection 53 with a slide 55 on rod 56. Slide 55 has a cam follower 51 so that it is raised and lowered by cam 52. Spring 57 urges follower 51 onto cam 52. The side tucker 33 is moved in and out by a link connection 54 with the bell crank 34.

The up and down movement of side tucker 33, by means of cam 52, also serves to swing the side plate 60 between horizontal and vertical positions. Plate 60 is connected to slide 55 by a link 62, see Fig. 6. When the cam 52 raises follower 51 as shown in Fig. 6, this raises not only the side tucker 33, but also swings up the plate 60 to upright position as shown also in Fig. 8. The opposite plate 63 is fixed in upright position and does not move. The plates 60 and 63 have adjustable shelves like 64 for boxes of different depths.

When plate 60 swings up to open the box as shown in Fig. 8, the box is thus gripped or held between the plates 60 and 63 and their shelves like 64 while the various tuckers are operating.

As shown in Fig. 8, the side tucker 33 is fixed to the top of arm 50 which also carries a stud 65 serving as a hinge support for a bracket 66 which carries an adjustable presser 67 which offers a resilient abutment against which the end flap 9 is folded by the end tuckers 70. The presser 67 is urged towards the end tucker 70 by a spring 68. The other side tucker 32 has a similar presser 69.

As shown in Figs. 9 to 12, the end tucker 70 is in two parts, of which the part 71 may be designated a primary tucker and the part 72 a secondary tucker. The tucker 71 has a bracket 73 which adjustably carries a curved plate 74 which acts as a guide for the end flap. Plate 74 extends beyond the outer end 75 of the tucker 72 so that guide 74 can move relatively to the tucker 72 to fold the end of flap 9 at its outer fold line 76 as shown in Fig. 10. The hinge axis 77 of both the tuckers 71 and 72 is adjacent and parallel to the inner fold line 78 of the box. The tucker 71 in moving to fold the outer end of the flap as shown in Fig. 11 brings the guide 74 to a position where its outer end 79 is just underneath the top 13 of the box to provide a path leading into the open end of the box, whereby subsequent movement of tucker 72 completes the tucking operation while the guide 74 guides the folded outer end of the flap into the box.

As shown in Fig. 12, in their lowermost positions, the end 79 of tucker 71 and the tucker 72 are horizontal in line with the bed 21 so as to not obstruct the ejection of the finished box.

The bracket 73, as shown in Figs. 9, 10 and 11 rests on an adjustable stop 80 which is adjusted

to bring the end of guide 79 to the horizontal position shown in Fig. 12.

The tucker 71 is operated by a cam 81 having a cam follower 82, on a lever 83 connected to a link 84 adjustably connected to bracket 73 as shown at 85 in Fig. 12. The follower 82 is shown above cam 81 in Fig. 9 because the stop 80 is supporting the bracket 73. The tucker 72 has a bracket 86 connected to a link 87 operated by lever 88 having a cam roller 89 for cam 90. The cams 81 and 90 are fixed to the shaft 27. As shaft 27 rotates, cam 81 picks up its roller 89 and its elevated position is shown in dotted lines at 91 where it is resting on the dwell 92 with the parts in the position shown in Fig. 10. In rising, bracket 73 picks up tucker 72 and elevates it to the position shown in Fig. 10 although this elevating could be done by cam 90. As follower 88 reaches the dwell 92, the rise 93 on cam 90 operates the tucker 72 to vertical position shown in Fig. 11 to complete the tucking.

In the form of end tucker shown in Figs. 9 to 11, the guide 74 is concentric with the hinge axis 77, but in some cases, the box front, when the box is unfolded to open position, is concave as shown at 100 in Fig. 16. In this case, the concentric guide 74 would not lead the end of the flap into the box. To overcome this, the guide 101 on the primary tucker is made eccentric with the hinge axis 102 of the tuckers, that is the distance from axis 102 to the inner end 103 of guide 101 is greater than the distance from axis 102 to the outer end 104 of the guide and the latter distance is less than the radius of the secondary tucker 105. The guide 101 has a hinge support on bracket 106.

For example, guide 101 has a plate 107 having an aperture 108 through which extends a stud 109 having a compression spring 110. Plate 107 has apertures 111, 112, see Fig. 17 which loosely fit on pins 113, 114 on a plate 115 adjustably secured on bracket 106 by a screw 116. As shown in Fig. 14, the outer end 104 of guide 101, when the latter is in its elevated position, arrives at a position low enough to enter the uppermost front 100 of the box in position to guide the folded end 117 of the flap into the box as shown in Fig. 15. In so doing, the secondary tucker 105 raises the guide 101 against the action of spring 110, to elevate the concave front 100 for entry of the flap end 117.

Figs. 18 and 19 illustrate a modified form of end tucker for a shallow box 120 having a long end flap 121. In this case, the guide 122 of the primary tucker is provided with a guide portion 123 which extends at an acute angle to the bracket 124. In other words, the distance from the outer end 125 of the guide 123, to the hinge axis 126 of the tuckers is less than in the form shown in Fig. 14 and small enough to fold the end 121 down so that when both one primary tucker 122 and the secondary tucker 128 are later operated as above described, the flap end 121 will be guided into the box by the guide 123.

To adjust the end tuckers for boxes of different dimensions, as will be apparent from various forms in Figs. 12 to 19, the primary tucker or guide like 74 in Fig. 12 may be removed and other sizes or types substituted, and the position of guide 74 on bracket 73 may be adjusted by screw 129. The same thing applies to the primary tuckers shown in the other figures. Also the secondary tucker 72 has a size about the same as the end of the box and various sizes of tucker 72 may be used instead, tucker 72 being removably held on a base 130 by screw like 131. The same applies

to the secondary tuckers in the other figures. For various shallow boxes, the plate 72 may be omitted and the support 130 in Fig. 12 then serves as the secondary end tucker. The secondary tucker instead of having a plate like 72, as shown in Figs. 18 and 19 may have a strip 132 fixed to the end of the base 130 by screws like 134. The advantage of this, for a shallow box, is that the base 130 has a rear portion 135 which is on a level with the bed 21 while the outer portion of base 130 and the strip 132 are at a lower level as indicated in 136 in Fig. 18. As the primary guide 122 swings up, the secondary tucker 128, 130 being horizontal, the guide 123 bends the flap 121 over the end of strip 134 with the outer end of the flap 121 closer to the hinge axis 126 and hence in a better position to enter into the box, than would otherwise be the case.

After the end flap 9 has been tucked in, the end tucker like 70 in Fig. 12 is returned to open position so as to not obstruct the ejection of the finished box, the side flap tuckers 32 and 33 are retracted and the plate 60 is swung down to position shown in Fig. 1, ready for the next box blank.

The bottom blank on the stack 17 may be released one at a time by a suitable escapement 137, see Figs. 1 and 3.

If desired, the finished box may be ejected by the next blank which is advanced by fork 18. Preferably, however, the ejector is a separate item from the fork 18. As shown in Figs. 2, 4 and 9, fork 18 is connected with a tube 138 in which slides a rod 139 having an ejector 140 pivotally mounted thereon as indicated at 141. The ejector 140 is in the form of a hollow head urged upwardly by spring 142. The forward movement of ejector 140 is limited by a rubber bumper 143 on the frame of the machine. Tube 138 has a spring 144, see Fig. 4, which urges ejector 140 forwardly. When ejector 140 is at its forward position, it has ejected the finished box, and as fork 18 brings a new blank to the folding station 6, fork 18 cams the ejector 140 down by a front end 145 acting on the outer surface 146 of the ejector. When the fork makes its return stroke, the tube 138 contacts a spring, see Fig. 2, on rod 139 to retract the ejector 140. This is described in further detail in application Serial No. 343,837 filed March 23, 1953, for Knock-Out for Box Making Machine which is a division of the present application and discloses and claims the knock-out shown herein.

Various modifications may be made in the invention without departing from the spirit of the following claims.

I claim:

1. A box-making machine comprising a bed, means for feeding to said bed a box having an end flap projecting therefrom, said end flap having an inner fold line where it joins the box and an outer fold line adjacent the end of said flap, a primary tucker and a secondary tucker, said tuckers having independent hinge supports on the same axis adjacent said inner fold line, said secondary tucker having a size comparable to the end of said box, said primary tucker having a guide thereon beyond the outer end of said secondary tucker, a presser device for pressing the flap towards said tuckers, means for moving said primary tucker relatively to said secondary tucker to urge said guide against said flap and fold said flap at its outer fold line and position said guide to form a path leading into the box, and independent means for operating said sec-

ondary tucker to tuck said flap in the box while guided by said guide.

5 2. A box-making machine for tucking the end flap of an open box, said flap having inner and outer fold lines, said machine comprising primary and secondary tuckers, said tuckers having independent hinge supports on the same axis, cam means for moving said primary tucker relatively to said secondary tucker to fold said flap at said outer fold line, and cam means for moving said secondary tucker relatively to said primary tucker to fold said flap on said inner fold line.

15 3. A box-making machine for tucking the end flap of an open box, said flap having inner and outer fold lines, said machine comprising primary and secondary tuckers, said tuckers having independent hinge supports on the same axis, means for initially moving said primary tucker relatively to said secondary tucker to fold said flap at said outer fold line, and means for moving said secondary tucker relatively to said primary tucker to fold said flap on said inner fold line.

20 4. A box making machine comprising a bed, means for moving a collapsed box along said bed, said box having an end flap projecting foremost therefrom, said flap having a fold line at the box and an outer fold line adjacent the end of said flap, means at one end of said bed for supporting the box with its end flap projecting therefrom beyond said bed, a primary end tucker having a guide, a secondary end tucker, said tuckers having independent hinge supports on the same axis at the end of said bed, means for operating said primary tucker for movement of said guide relatively to said secondary tucker to fold said flap at said outer fold line and position said guide to lead the folded flap into the box, and independent means for operating said secondary tucker to advance the flap to tucked position in the box while guided by said guide.

25 5. A box making machine according to claim 4, said guide having a movable support, spring means urging said guide to a position where the outer end of said guide is at a lesser distance from said axis than the radius of said secondary tucker, said secondary tucker acting against said spring to raise said guide while approaching the tucked position of said flap.

30 6. A box making machine for tucking the end flap of a box, said flap having a fold line at the box and an outer fold line adjacent the end of said flap, said machine comprising a primary end tucker and a secondary end tucker, said primary tucker comprising a bracket, separate means pivotally supporting said bracket and said secondary tucker, a guide, a movable support for the inner end of said guide on said bracket, a spring urging said guide to a position with its outer end in the path of said secondary tucker, said spring urging said guide to a position to guide the end of said flap lower than the normal open position of the box front, means for operating said secondary tucker to engage and raise said guide as said secondary tucker advances, and means for operating said bracket.

35 7. A box making machine according to claim 6, said means which pivotally supports said bracket having an axis, and means adjustably holding said support on said bracket at a selected one of different distances from said axis.

40 8. A box making machine according to claim 6, said separate means pivotally supporting said bracket and said secondary tucker having the same horizontal axis and comprising means sup-

porting said secondary tucker above and in the path of said bracket when said bracket is in a lower position, said means for operating said bracket comprising means for elevating said bracket about said axis.

9. A box making machine for tucking the end flap of a box, said flap having a fold line at the box and an outer fold line adjacent the end of said flap, said machine comprising a primary end tucker and a secondary end tucker, a presser for pressing an inner portion of the flap on said secondary tucker, separate means supporting said tuckers for independent movement on the same hinge axis, said primary tucker having a guide, means for advancing said primary tucker relatively to said secondary tucker to fold the flap at said outer fold line, said advancing means thereafter positioning said guide to lead the end of the flap into the box, and means for subsequently advancing said secondary tucker relatively to said primary tucker to fold the flap at the box fold line and complete the tucking.

10. A box making machine according to claim 9, said guide comprising a curved plate substantially concentric with said hinge axis and arranged beyond the outer end of said secondary tucker.

11. A box making machine according to claim 9, said primary tucker comprising a bracket extending from said hinge axis, said guide comprising a curved plate substantially concentric with said hinge axis and means for adjustably fastening said plate on said bracket for movement of said plate beyond the outer end of said secondary tucker.

12. A box making machine comprising a bed, means for moving a collapsed box along said bed, said box having an end flap projecting foremost therefrom, said flap having a fold line at the box and an outer fold line adjacent the end of said

flap, means at one end of said bed for expanding the box with its end flap projecting therefrom beyond said bed, means at said end of said bed for tucking the end flap in said box, and means for operating said expanding means to hold the expanded box during operation of said tucking means, said tucking means comprising a primary end tucker and a secondary end tucker, a presser for pressing an inner portion of the flap on said secondary tucker, separate means supporting said tuckers for independent movement, said primary tucker having a guide, means for advancing said primary tucker relatively to said secondary tucker to fold the flap at said outer fold line, said advancing means thereafter positioning said guide to lead the end of the flap into the box, and means for subsequently advancing said secondary tucker relatively to said primary tucker to fold the flap at the box fold line and complete the tucking.

13. A box making machine according to claim 12, said means for advancing said primary tucker and said means for advancing said secondary tucker being operative to move said tuckers between a lower position and an upright position, and means for ejecting the open tucked box over the top of said primary and secondary tuckers when in their lower positions.
